(57) **CLAIM**

The ornamental design for a tire, as shown and described.

DESCRIPTION

FIG. 1 is a front view of the tire showing my new design;
FIG. 2 is a front perspective view thereof;
FIG. 3 is a top elevation view thereof;
FIG. 4 is an enlarged partial top elevation view thereof;
FIG. 5 is a left side view thereof; and,
FIG. 6 is a right side view thereof.

The dashed lines shown in FIGS. 2, 5, and 6 represents the border between the claimed tire and the unclaimed interior of the tire, and forms no part of the claimed design.

1 Claim, 6 Drawing Sheets

FIG. 1

FIG. 2

FIG. 3

FIG. 4

FIG. 5

FIG. 6
